FIG. I.

FIG. II.

FIG. III.

FIG. IV.

FIG. V.

FIG. VI.

INVENTOR:

WALTER H. RICHMAN,

*By Arthur C. Page,
Attorney.*

Patented Feb. 12, 1929.

1,701,636

UNITED STATES PATENT OFFICE.

WALTER H. RICHMAN, OF KIRKWOOD, NEW JERSEY.

CONTAINER.

Original application filed April 26, 1923, Serial No. 634,653. Divided and this application filed September 30, 1927. Serial No. 223,100.

My invention is particularly applicable to sheet metal cans used in the transportation and storage of dairy products. Such cans are used by wholesalers to deliver milk, 5 cream, ice cream, frozen custards, etc., to retailers, and are used by the latter to hold such products while they are being dispensed; the emptied cans being thereafter returned to the wholesalers to be refilled and again 10 distributed. Consequently, such cans must be extremely durable to withstand the rough handling and stresses and wear to which they are inevitably subjected. Moreover, as such containers are retained in salt ice water to 15 preserve their contents, their bodies must be permanently liquid tight and, to prevent contamination of their contents, they must be adapted to be substantially hermetically sealed by closures which can be instantly 20 opened and shut, to facilitate dispensing of their contents. Furthermore, such containers should not have any internal corners or recesses or joints which cannot be readily cleaned of every vestige of their contents, by 25 mechanical means, for such products readily and rapidly decompose.

Therefore, the object and effect of my invention is to provide containers having the characteristics above contemplated. However, it is to be understood that I do not desire to limit my invention to such specific use. 30

My invention includes the various novel features of construction, arrangement, and procedure hereinafter specified.

35 In said drawings; Fig. I is an elevation, partly in section, showing a container embodying my invention and adapted for holding ice cream and similar dairy products.

Figs. II to V inclusive are fragmentary 40 vertical sectional views showing successive stages in the formation of the bottom plate, and its joint with the container body, in the form of my invention shown in Fig. I.

Fig. VI is a fragmentary vertical sectional view of the bottom of a container, 45 showing a modified form of my invention.

Referring to the form of my invention shown in Fig. I; the can body 1 has the removable lid closure 2, conveniently provided 50 with the rigid handle 3; having its opposite ends 4 welded to the top of said closure 2. Said can body 1 is conveniently formed of primarily flat sheet steel, preferably low carbon steel, by first bending such sheet to cylindrical form and then uniting its longitudi-

dinal abutting edges 6 conveniently by an electrical or gas welding operation. However, I prefer to reinforce said can body at its upper edge and provide a bead 7 as a seat for said closure 2, by twice folding the edge 60 of the metal backward upon itself, to the configuration indicated in Fig. I, before the metal is bent to cylindrical form, as above described.

Said can body 1 is provided with the bottom closure 8 which is curved to form an acute edge 9, forming a filleted corner inside the can to facilitate cleaning the latter, and has the cylindrical flange 10 which may be of the same diameter as said can body 1 and 65 welded thereto, as indicated at 11. I find it convenient to form said bottom closure 8 with a reinforcing chime including a tubular toric bead 13 connected with the upturned edge 9 of said closure by the cylindrical zone 70 14. Such a bottom closure may be conveniently formed by the successive steps indicated in Figs. II to V inclusive, wherein the closure plate 8, which is primarily plane, is dished, by a pressing operation, to form the circular zone 14; then swaged to form the toric bead 13, conveniently by pressing the inner region of said closure 8 outwardly over a forming ring 16, which may be left in said 75 bead to reinforce the latter. Said cylindrical flange 10 is formed by upturning the primarily plane flange 17, and said edge 9, if left blunt by a pressing operation, may be sharpened to an acute angle in contact with said flange 10, by a spinning swaging operation, with any suitable means; for instance 80 the roller 18.

In order to facilitate the operation of welding said flange 10 to the body 1 at the junction 11; I prefer to initially outwardly converge the upper edge of said flange 10, as indicated at 19 in Fig. IV, so that the bottom edge of said body 1 fits therein, as indicated 95 in that figure. With said body 1 and its bottom closure 8 thus assembled, as in Fig. IV; the thus overlapped edges thereof may be welded together conveniently between opposed rollers 20 and 21 as indicated in Fig. V; said rollers forming the opposite electrodes of the welding circuit and being 100 pressed toward each other so as to smooth the welded joint while the metal is plastic with the heat of the welding operation.

Thereafter, the container above described, including the body 1 and the bottom closure 110

8, and also the top closure 2, may be coated with tin by any convenient method or means, so that the structure is completely formed without any rivets or solder. One of the 5 advantages of such construction is that such structures may be repeatedly retinned without contamination and loss of the tinning bath, which would be polluted by the immersion of any soldered container therein, be- 10 cause the solder, largely composed of lead, melts in and mixes with the molten tin, rendering the latter unfit for subsequent use for tin plating.

However, in some forms of my invention; 15 I prefer to leave the bottom edge of the can body and the upper edge of the bottom closure permanently overlapped, so as to afford a duplicate thickness to reinforce the container against transverse stresses at that 20 joint. For instance, as shown in Fig. VI; the cylindrical can body 22, which may be otherwise conveniently formed like the can body 1 above described, is inwardly con- 25 verged at its lower edge, conveniently by a rotary spinning operation, to a cylindrical zone 24 of less diameter, to afford an externally recessed cylindrical seat 25 for the upwardly extending cylindrical flange 26 of the bottom closure 27, which may be formed like 30 the bottom closure 8 above described, but may also have the annular recessed seat 28 to receive the inwardly turned bottom edge 29 on said body 22.

Said container body 22 and its bottom 35 closure 27 may be joined by continuously circumferentially welded joints, or by a succession of spot welds which overlap each other, or by a series of spot welds 30 in circumferentially spaced relation. I find that 40 the latter, which is the cheapest of the three methods of welding, suffices, in view of the fact that the structure is subsequently tinned both inside and outside.

Of course, it is to be understood that it is 45 unnecessary to provide a container bottom joint of the form indicated in Fig. VI with the tubular chime 13 indicated.

As aforesaid, I prefer to weld all my container joints for the reason that they may 50 be coated with pure tin, and repeatedly retinned; whereas, any solder included in such containers fuses off in the molten tin bath and renders the latter unfit for coating because of the mixture therewith of the different 55 metallic elements of the solder. However, it is obvious that containers, otherwise as described, may have soldered or riveted joints.

This application is a division of my applica- 60 tion for Letters Patent of the United States Serial No. 634,653, filed April 26, 1923.

Therefore, I do not desire to limit myself to the precise details of construction and arrangement or method of procedure herein set 65 forth, as it is obvious that various modifica-

tions may be made therein, without departing from the essential features of my invention, as defined in the appended claims.

I claim:

1. The process of forming a container bottom closure plate, which includes pressing a primarily plane circular sheet of metal to offset a circular area in concentric position therein, bounded by a circular tubular zone extending transversely to a plane perimetral 70 flange; forming an inwardly curved hollow toric bead at the junction of said zone and flange; and bending said plane flange to form a circular tubular flange, and thus including 75 said bead as part of a tubular toric chime 80 ring.

2. In a container, the combination with a cylindrical tubular body; of a bottom closure including a circular plate, bounded by a cylindrical tubular zone; said plate having an acute angular edge upwardly inclined at the circumference of said zone; a tubular toric chime ring at the lower edge of said zone; a cylindrical flange exterior to said zone; said cylindrical flange being of the 90 same outside diameter as said body and circumferentially welded to said body; and a solid ring in said tubular ring.

3. In a container, the combination with a cylindrical tubular body; of a bottom closure 95 including a circular plate, bounded by a cylindrical tubular zone; said plate having an acute angular edge upwardly inclined at the circumference of said zone; a tubular toric chime ring at the lower edge of said zone; a cylindrical flange exterior to said zone; said cylindrical flange being of the same outside 100 diameter as said body and circumferentially welded to said body.

4. The process of forming a container bottom closure, which includes pressing a primarily plane sheet of metal to offset a circular area thereof, bounded by a circular tubular zone, extending transversely to a perimetral flange; forming a hollow toric bead at the 110 junction of said zone and flange; bending said flange to circular tubular form, around said zone, thus including said bead as part of a tubular toric chime ring; and swaging the margin of said circular area to an acute 115 edge, in contact with said flange.

5. The process of forming a container bottom closure, which includes pressing a primarily plane sheet of metal to offset a circular area thereof, bounded by a circular tubular 120 zone, extending transversely to a perimetral flange; bending said flange to circular tubular form, around said zone; and swaging the margin of said circular area to an acute edge, in contact with said flange.

In testimony whereof, I have hereunto signed my name at Kirkwood, Camden Co., New Jersey, this 25th day of July, 1927.

WALTER H. RICHMAN.
